United States Patent Office

Des. 196,187
Patented Sept. 3, 1963

196,187

SUGAR BOWL OR SIMILAR ARTICLE

Howard Treu, Greenville, Conn., assignor to The Block
China Company, New York, N.Y., a firm

Filed Feb. 11, 1963, Ser. No. 73,542

Term of patent 7 years

(Cl. D44—15)

FIG. 1 is a plan view of a sugar bowl or similar article showing my new design;

FIG. 2 is a front view, partially in section, taken on broken lines 2—2 of FIG. 1;

FIG. 3 is a right side elevational view thereof.

I claim:

The ornamental design for a sugar bowl or similar article, as shown.
